UNITED STATES PATENT OFFICE

FRANK W. KARLI, OF VALLEY SPRINGS, SOUTH DAKOTA.

SEED-CORN STRINGER.

1,082,875.

Specification of Letters Patent. Patented Dec. 30, 1913.

Application filed April 2, 1913. Serial No. 758,293.

To all whom it may concern:

Be it known that I, FRANK W. KARLI, a citizen of the United States, and a resident of Valley Springs, in the county of Minnehaha and State of South Dakota, have invented certain new and useful Improvements in Seed-Corn Stringers, of which the following is a specification.

My invention relates to means for stringing seed-corn preparatory to suspending the same for drying and curing.

The primary object of the invention is the production of an improved device for stringing corn, simple and economical in construction and thoroughly reliable in operation.

With this and other objects in view, the invention will be fully understood from the following description, reference being had to the accompanying drawings, forming a part of this specification, in which like characters of reference indicate corresponding parts in both views, of which,—

Figure 1 is a side elevation of the preferred embodiment of my invention, and Fig. 2 is a horizontal section of the bracket-arm, taken on the line 2—2 of Fig. 1, associated members being omitted.

In the illustrations, 1 is a bracket-arm, 30 adapted to be removably secured to an upright support as a studding, or post, 2. My means for securing the bracket-arm preferably comprises a clamp, having jaws, as 3, adapted to embrace the upright, 2, and secured on opposite sides of the bracket-arm, by means of bolts, 4 and 5, passing through both jaws and bracket-arm. The sides of the bracket-arm, adjacent the jaws, 3, are tapered slightly, to permit the jaws being 35 adjusted toward and from each other to suit uprights of divers dimensions. The clamp is secured to the upright by tightening the nut, 5^a and the thumb-nut, 4^a, into firm engagement with the adjacent jaw. The inner 40 faces of the jaws are provided with studs, 6, serving to prevent displacement of the former when secured to the upright. Horizontally-disposed members, rotating in opposite directions, serve to twist the twine between the ears of corn; and for this purpose I prefer to employ intermeshed spur-gears, as 45 7 and 8, journaled on bearings, 9, below the bracket-arm. The upper side of the gear, 8, is provided with bevel teeth, 10, intermeshed with a bevel-gear, 11, secured upon a cranked-shaft, 12, journaled in suitable

bearings, 13, upon the bracket-arm. From the spur-gears, 7 and 8, depend double hooks, 14, disposed diametrically of the rotating members. These hooks support and separate the strands; and may be provided in various forms, yet preferably, as illustrated, formed of a continuous wire, the ends of which are bent upwardly and secured to the spur-gears, and the middle portion, 15, bent upwardly in a plane parallel to the end portions, thus forming the hooks, 14. As the middle, or horizontal portion, is shorter than the distance between the end portions, the hooks are somewhat inwardly disposed. My purpose in constructing the hooks in this manner is to facilitate the removal of the completed strings of corn which are rather heavy. It is apparent that when one side of one of the loops is lifted from its hook, the loop will easily slip over the horizontal link, 15, and finally leave the companion hook without further effort by the operator. For convenience, I provide a vertical spindle, 16, to carry a ball of twine, 17; and a twine-cutting blade, 18, secured to the arm.

In the practical operation of my novel device, a twine is cut approximately twice the length of the string of corn it is proposed to weave, and the ends then tied together, forming an endless, or double strand, 19, the looped ends of which are hung upon the hooks, 14. In the depending bights is then laid the first ear of corn, represented at 20. The ear 21 then is placed between the strands, transversely of the first ear, and the crank turned which imparts rotation to the spur-gears, whereby the strands are crossed above the ear. The ears, 22, are 90 successively placed between the strands and in a similar manner the strands are woven about each ear. At 23 is represented an ear about to be placed, preparatory to twisting the strands. When the string of corn is completed the loops are removed from the hooks and suspended in any manner suitable to the curing process. Obviously the spur-gears may be replaced by mechanical equivalents, such as pulleys connected by a crossed belt, etc.

Having thus described my invention what I claim as new and desire to secure by Letters Patent, is,—

In a device of the class described, the combination with a suitable support, of a bracket-arm, spur-gears mounted on said

bracket-arm for rotation in opposite directions, each to the other; companion hooks carried by said spur-gears, adapted to suspend an endless twine and hold the side strands in spaced relation each to the other; and means for imparting rotation to said spur-gears, whereby the strands will cross each other.

In witness whereof I have hereunto signed my name in the presence of two subscribing witnesses. 10

FRANK W. KARLI.
